INVENTOR:
JOHN J. B. ARTER

BY: *Frank Oldham*

ATTORNEY

UNITED STATES PATENT OFFICE.

JOHN J. B. ARTER, OF BIRMINGHAM, ENGLAND.

ORDNANCE.

1,324,098.

Specification of Letters Patent.

Patented Dec. 9, 1919.

Application filed July 6, 1918. Serial No. 243,613.

To all whom it may concern:

Be it known that I, JOHN JAMES BEDNEY ARTER, subject of the King of Great Britain, residing at James Works, Greet, juxta Birmingham, in the county of Warwick, England, have invented a new and useful Improvement in Ordnance; and I do hereby declare the following to be a full, clear, and exact description of the same.

10 My invention comprises improvements relating to guns, *i. e.*, field, heavy siege or howitzers as distinguished from machine guns.

In practice it is necessary to keep a record 15 of the number of projectiles which have been fired from each gun or battery for which purpose the gunners have to count the number of projectiles inserted or the 20 number of empty cartridge cases after firing, but this method is both inconvenient and unreliable.

The object of the present invention is to provide guns with a reliable automatic 25 counting or recording apparatus and in accordance therewith the recoil apparatus of the gun is connected to a tachometer or equivalent counting device through the medium of a trip mechanism which is operated by the movement of the recoil apparatus.

30 In the accompanying drawings:

Figure 1 is a side elevation of a gun fitted with my invention.

Fig. 2 is a view in side elevation upon an enlarged scale showing the trip mechanism and its attachment to the tachometer.

Fig. 3 is a sectional view in side elevation showing the tachometer drive mechanism.

Fig. 4 is a sectional end view corresponding with Fig. 3.

40 The tachometer *a* may be of any suitable construction, while the trip mechanism consists of a pivoted catch or lever *b* connected to the tachometer *a* by a cable *c*, or other equivalent mechanism, the pivoted catch *b*, 45 being so arranged that it is actuated by the movement of the recoil of the gun *d* in the one direction, but not on the return movement.

Referring to Figs. 3 and 4 the cable *c* is 50 connected to a sleeve *e* loosely mounted concentrically with the driving spindle of the tachometer. The sleeve *e* is fitted internally with a pivoted pawl *f* upon which acts a spring *f¹*. The tachometer driving spindle *g* carries a ratchet wheel *h* which is fixed 55 thereon and the pawl *f* engages with the

ratchet *h*. A coil spring *k* is provided one end of which is attached to a fixed part of the tachometer casing and the other end of which is attached to the sleeve *e*. The arrangement is such that when the gun is fired the recoil moves the lever *b* into the position shown in dotted lines in Fig. 2, thus pulling on the cable *c*. The pull upon the cable *c* rotates the sleeve *e* thus causing the 60 pawl *f* to drive the ratchet wheel *h* and the spindle *g*. In this way the tachometer indicates that a shot has been fired. After the recoil action has taken place and the gun moved into its original position the coil 65 spring *k* will move the sleeve *e* back into its original position thus taking up the slack in the cable *c*.

The tachometer *a* is preferably arranged to record the total number of projectiles 70 which have been fired and also the daily total, the daily total mechanism being adapted to be restored to zero whenever required.

What I claim then is:—

1. The combination with a gun of a tachometer and a pivoted lever for driving said tachometer, one end of said lever being disposed in the path of the recoil apparatus, and a flexible member connecting the other end of said lever with a rotatable driving 80 sleeve upon the tachometer, and adapted to cause rotation of said driving sleeve.

2. The combination with a gun of a tachometer and a pivoted lever for driving said tachometer, one end of said lever being disposed in the path of the recoil apparatus and a member connecting the other end of said lever with a driving sleeve upon the tachometer, said driving sleeve having a pawl in engagement with a ratchet wheel 90 upon the driving spindle of the tachometer, and means for returning said driving sleeve to its original position after each operation.

3. The combination with a gun of a tachometer and a pivoted lever for driving said tachometer, one end of said lever being disposed in the path of the recoil apparatus and a member connecting the other end of said lever with a driving sleeve upon the tachometer, said driving sleeve having a 100 pawl in engagement with a ratchet wheel upon the driving spindle of the tachometer and a coil spring having one end fixed and the other end attached to said driving sleeve, for returning said driving sleeve to its original position after each operation.

4. The combination with a gun of a ta-

chometer and a pivoted lever for driving said tachometer, one end of said lever being disposed in the path of the recoil apparatus, and a flexible member connecting the other 5 end of said lever with a rotatable driving sleeve upon the tachometer, and adapted to cause rotation of said driving sleeve, said driving sleeve having a pawl in engagement with a ratchet wheel upon the driving spindle of the tachometer, and means for returning said driving sleeve to its original 10 position after each operation.

5. The combination with a gun of a tachometer and a pivoted lever for driving said 15 tachometer, one end of said lever being disposed in the path of the recoil apparatus,

and a flexible member connecting the other end of said lever with a rotatable driving sleeve upon the tachometer, and adapted to cause rotation of said driving sleeve, said 20 driving sleeve having a pawl in engagement with a ratchet wheel upon the driving spindle of the tachometer, and means for returning said driving sleeve to its original position after each operation, and a coil 25 spring having one end fixed and the other end attached to said driving sleeve, for returning said driving sleeve to its original position after each operation.

In testimony whereof, I have signed my 30 name to this specification.

JOHN J. B. ARTER.
